UNITED STATES PATENT OFFICE.

DEWEY M. KENNEDY, OF ROCHESTER, NEW YORK, ASSIGNOR OF ONE-HALF TO
BENJAMIN H. KENNEDY, OF ROCHESTER, NEW YORK.

CASTER.

1,342,448.

Specification of Letters Patent. Patented June 8, 1920.

Application filed August 11, 1919. Serial No. 316,611.

To all whom it may concern:

Be it known that I, DEWEY M. KENNEDY, of Rochester, in the county of Monroe and State of New York, have invented certain new and useful Improvements in Casters; and I do hereby declare the following to be a full, clear, and exact description of the same, reference being had to the accompanying drawings, forming a part of this specification, and to the reference-numerals marked thereon.

My present invention relates to casters and it has for its object to provide a simple, cheap and efficient device of this nature that can be easily applied or detached and a further object of the invention is to provide a caster that is convertible through a reassembly of the parts from the fixed type to the swivel type or vice versa. To these and other ends the invention resides in certain improvements and combinations of parts all as will be hereinafter more fully described, the novel features being pointed out in the claims at the end of the specification.

In the drawings:

Figure 1 is a side view of an article of furniture provided with casters constructed in accordance with and illustrating one embodiment of my invention; the one on the left being fixed and the one on the right being swiveled;

Fig. 2 is an enlarged fragmentary side view of the socket and contiguous parts when the socket is adjusted to hold the caster fixed;

Fig. 3 is a similar view with the socket arranged to swivel the caster;

Fig. 4 is a section on the line 4—4 of Fig. 3;

Fig. 5 is a section on the line 5—5 of Fig. 2;

Fig. 6 is a bottom view of the caster socket in the position of Figs. 3 and 4 showing the yoke in horizontal section, and

Fig. 7 is a perspective view of the socket.

Similar reference numerals throughout the several views indicate the same parts.

In the present embodiment of the invention, my improved caster is shown applied to a rolling child's crib and play coop indicated generally at 1 in Fig. 1. It rolls on four wheels, two of which are shown in the said figure at 2 and these are mounted in the manner of caster rollers on yokes 3. It is

desired by some to have all of the wheels 55 swivel while others like them fixed and in other instances, it is desirable to have the pair at one end and the pair at the other end swiveled. In the present instance, I have shown the last mentioned arrangement, 60 but a feature of my invention is the fact that through its use the manufacturer, in the first instance, or later the dealer may, with the same parts, produce any of these combinations.

Referring to Figs. 4 and 5, the lower rails 4 of the crib are of the cross section there shown and I bore these vertically as indicated at 5 to receive the shank 6 of the caster to the lower projecting end of which the 70 yoke 3 is swiveled at 7. I prefer to form the caster of the type in which the yoke swivels on the shank rather than the type in which these parts are relatively fixed and the shank turns in the socket. I run the shank 6 all 75 the way through the rail 4 and thread its upper projecting end at 8 to receive a nut 9 and washer 10.

Interposed between the top of the yoke 3 and the rail 4 is a socket plate 11 perforated centrally at 12 to receive the shank 6. I will first describe this socket in the position and possessing the functions of Figs. 2 and 5 and as shown at the left in Fig. 1. The socket preferably consists of a sheet metal 85 plate perforated at the center as described and blanked out in a manner to provide a set of four upwardly turned ears or lugs 13 located in pairs at the ends of the blank and leaving intermediate portions 14 which are 90 bent downwardly or in the opposite direction at the center to provide another set of spaced lugs. In Figs. 2 and 5, the socket plate is applied so that the four lugs 13 lock on each side of the rail 4 and prevent the 95 plate from turning while the body thereof is drawn up against the under side of the rail by the shank 6 and yoke 3. The shank is preferably of just the right length so that when the nut 9 is screwed tight it will draw 100 the plate firmly against the rail without undue strain upon the swivel connection 7 between the said shank and the yoke 3 and to further anchor the plate and at the same time space it slightly, I provide it with 105 transverse bosses 15 extending between the pairs of lugs 13 located on opposite sides of the aperture 12, the spacing being for a pur-

pose that will hereinafter appear. This brings yoke 3 or the head thereof snugly between the downwardly turned central lugs 14 and the caster is fixed to travel in one direction only.

When it is desired that the caster shall swivel about I simply turn the plate 11 over and run the shank 6 therethrough from the other side as shown in Figs. 3, 4 and 6, 10 whereupon the intermediate lugs 14 lock upon opposite sides of the rail 4 and the lugs 13 extend downwardly instead of upwardly. But they are so far removed from the central aperture 12 of the shank 6 that they are not 15 in the rotary path of the yoke 3 and clear the latter so that they become inoperative and permit the yoke to turn upon its swivel connection 7 and the wheels to track correspondingly in any desired direction. In 20 this position of the socket plate and with the shank 6 of the given length required for the first described assembling, the said plate lies closer against the rail 4, as shown in Fig. 4, and the lower or swivel end of the 25 shank projects a greater distance when the nut 9 is tightened, the projection being increased to a degree equal to the height of the bosses 15. This is just enough to prevent the yoke 3 from binding against the 30 socket plate and allows it sufficient play to turn freely as a swivel should, though the flat surface of the head of the yoke bears against the bottom of the socket plate as before.

35 It will be seen that it is as easy to assemble the device one way as the other while it is a simple operation at any time to reverse the socket plate and produce the different function.

10 I claim as my invention:

1. In a caster, the combination with a yoke, a shank secured thereto and a wheel within the yoke, of a socket plate having upwardly extending lugs for locking 45 the socket to the support and downwardly

extending lugs to lock the yoke against turning.

2. In a caster, the combination with a yoke, a shank secured thereto and a wheel within the yoke, of a detachable socket plate for 50 the shank reversible thereon and having upper and lower sets of lugs respectively extending in opposite directions, either set being adapted to lock the socket to a support and only one set being adapted to lock the 55 yoke against turning when disposed in proximity thereto.

3. In a caster, the combination with a yoke, a shank secured thereto and a wheel within the yoke, of a detachable socket plate 60 for the shank reversible thereon and consisting of a centrally perforated sheet metal blank having central lugs on its lateral edges turned in one direction and adapted to either lock the socket to a support by embracing 65 the latter or the yoke against rotation according to the relative position of the yoke and shank and having end lugs on its lateral edges extending in the opposite direction and adapted to similarly lock the socket to 70 the support or to clear the yoke and permit of its rotation.

4. In a caster, the combination with a support, a yoke, a shank secured to the latter at one end and extending through the support, 75 a securing device on the other end of the shank and a wheel within the yoke, of a detachable socket plate for the shank reversible thereon and having upper and lower sets 80 of lugs respectively extending in opposite directions, either set being adapted to lock the socket to the support and only one set adapted to lock the yoke against turning when disposed in proximity thereto, the socket plate being further provided on one 85 side with members adapted to space it from the support when the yoke is locked against turning.

DEWEY M. KENNEDY.
